*Fig. 3**Fig. 6**Fig. 5**Fig. 4**Fig. 7*FIG. 1 is a perspective view of a tire embodying our new design, it being understood that the full line portion is repeated throughout the circumference of the tire, shown by means of broken lines;

FIG. 2 is an enlarged fragmentary side elevational view of the full line portion shown in FIG. 1;

FIG. 3 is a further enlarged fragmentary plan view of the full line portion shown in FIG. 1;

FIG. 4 is a sectional view taken substantially on the plane indicated by line IV-IV of FIG. 3, but on the same scale as FIG. 2;

FIG. 5 is a detailed sectional view taken substantially on the plane indicated by line V-V of FIG. 4;

FIG. 6 is a fragmentary perspective view taken substantially on the plane indicated by line VI-VI of FIG. 3, but on a larger scale;

FIG. 7 is a fragmentary perspective view taken substantially on the plane indicated by line VII-VII of FIG. 3, but on a larger scale; and

FIGS. 8, 9, 10 and 11 are detailed sectional views taken

substantially on the planes indicated by lines VIII-VIII, IX-IX, X-X and XI-XI of FIG. 3, but on the same scale as FIG. 4.

The characteristic features of the design for the tire disclosed reside in a tread having grooves of decreasing width extending transversely across the tread alternately from opposite edges of the tread, forming transverse ribs of substantially uniform width therebetween, substantially as shown.

We claim:

The ornamental design for a tire, substantially as shown and described.
